(57) **CLAIM**

The ornamental design for a flow channel plate of a cartridge for medical testing equipment, as shown and described.

DESCRIPTION

FIG. 1 is a perspective view of a flow channel plate of a cartridge for medical testing equipment showing our new design;

FIG. 2 is a front view thereof;

FIG. 3 is a top plan view thereof;

FIG. 4 is a right side view thereof;

FIG. 5 is an enlarged view of the portion defined by crop lines 5-5 in FIG. 1; and,

FIG. 6 is an enlarged view of the portion defined by crop lines 6-6 in FIG. 6.

The dashed lines depict portions of the flow channel plate of a cartridge for medical testing equipment that form no part of the claimed design. The dash-dotted lines depict the boundaries of the claimed design that form no part thereof.

1 Claim, 5 Drawing Sheets
